UNITED STATES PATENT OFFICE

RUSSELL J. GREEN, OF ENID, OKLAHOMA

HYDRATOR

Application filed July 14, 1931. Serial No. 550,739.

This invention relates broadly to electric refrigerators and has for an object to provide a defrosting tray, defrosting tank and hydrator for vegetables, combined in a single unit adapted to properly care for the vegetables and catch all of the defrost water and drain it into a separate compartment from which the defrost water may be readily drained without removing the unit from the refrigerator by means of a small faucet in the defrosting tank.

A further object is to provide a device of this type which will be neat and attractive in appearance and may be readily applied underneath the unit of an electric refrigerator without alterations to the refrigerator, and which, when applied, will be held against working away from applied position.

A still further object is to provide a device of this type including a casing which is open at the front and the top and is divided into two compartments, one for the reception of the vegetable tray and the other for the reception of the defrosting water tank, the top of the casing being closed by a removable tray which slopes from the sides and ends toward a diagonal inclined trough whereby the defrost water is led to one corner of the tray for draining into the water tank.

A still further object is to provide a device of this class in which the tray is provided with an outlet pipe at the low point thereof, which pipe is removably received in an opening in the top of the defrosting water tank and holds said tank against movement longitudinally in its compartment of the casing.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a perspective view of the device applied to an electric refrigerator,

Fig. 2 is a perspective view of the device,
Fig. 3 is a longitudinal sectional view taken on the line 3—3 of Fig. 2,

Fig. 4 is a longitudinal sectional view taken on the line 4—4 of Fig. 2,

Fig. 5 is a cross sectional view taken on the line 5—5 of Fig. 3, and

Fig. 6 is a fragmentary front elevation showing the spout and foot engaged on opposite sides of one of the shelf bars.

Referring now to the drawings in which like characters of reference designate similar parts in the various views, 10 designates an electric refrigerator of the usual and well-known type in which there is employed a unit 11 which, in the present embodiment, is disposed in the upper right-hand corner of the refrigerator above the bars 12 of the top shelf 13. The refrigerator is, as usual, equipped with shelves 14 and 15 below the unit. It will be understood that the electric refrigerator construction may be of any preferred type, the type illustrated being merely shown by way of example.

In carrying out the invention, I provide a casing 16 which is formed of metal and is open at the front and at the top. The casing is provided with a longitudinal partition 17 which divides the casing into two longitudinal compartments of substantially rectangular cross section. The casing is of sufficient height to be received on the shelf 14 underneath the unit 11, and is of sufficient length and width to present an air space around it on both the sides and back when in operative position.

For preventing displacement of the casing, the same is provided on the bottom, near the front, with a longitudinal foot 18, best shown in Fig. 3, which engages one bar 14' of said shelf, which latter is ordinarily formed of skeleton structure. The foot preferably is formed by bending down one edge portion of a longitudinal slot 19 formed in the bottom of the casing for a purpose which will be hereinafter described. The casing is furthermore provided with a pair of spaced transverse feet 20, best shown in

Fig. 5, on the bottom, which feet are secured to the bottom at the rear edge thereof in spaced relationship and may be formed in-

gral with the bottom or attached thereto by any suitable means. The three feet described all engage the bars of the shelf 14 and coact in preventing the casing slipping outwardly or sidewise from position underneath the unit 11.

The top of the casing 16 is closed by a tray 21 which slopes from the flange 22 thereof in all directions toward a diagonal trough 23 which extends from corner to corner of the tray bottom and has its low point preferably disposed at the rear right corner where the trough discharges into a drain pipe 24. The flange 22 of the tray is preferably substantially U-shaped in cross section, as best shown in Figs. 3 to 5, inclusive, so that the flange may be hooked over the top peripheral edge of the side walls and rear wall of the casing to removably secure the tray in place.

Disposed preferably in the right longitudinal compartment of the casing is a defrosting water tank 25 which, preferably, is rectangular in longitudinal and cross sections and preferably is formed of the same sheet metal as the tray and the casing. The tank is closed at the top, and, preferably, the side walls, end walls, top and bottom walls of the tank are formed integral and continuous, as there is no necessity in having a removable cover for this tank. The tank is provided in the top 26 with an opening 27 at the right rear corner, as best shown in Fig. 3, to receive the drain pipe 24 of the tray. The drain pipe projects downwardly into the tank 25 and serves as a stop to prevent the tank shifting forwardly in its compartment in the casing when the tray is applied. Of course, upon removal of the tray, the drain pipe is carried with it and permits of the tank being withdrawn forwardly from its compartment in the casing whenever desired.

The front wall 28 of the tank is provided at one bottom corner with a faucet 29 which preferably is provided with a spring-pressed 45 push valve 30 of the usual type, which it is not deemed necessary to illustrate as the faucet may be of any usual construction. The spout 31 of the faucet projects downwardly through the above-mentioned slot 19 in the 50 bottom of the casing, which slot thus permits of the spout being set back from the front edge of the casing. The tank, it will be noted, is shorter in length than the length 55 of the casing, so that the faucet itself is completely housed by the partition or division wall 17 of the casing, as well as by the side walls, slotted bottom wall, and the tray, as will be best seen by referring to Figs. 2 60 and 3.

The spout is of sufficient length to promote perfect drainage of the water. Furthermore, the spout engages one side of the shelf bar 14' of the shelf 14, and coacts with the lug 18, 65 which engages the other side of said shelf

bar 14' of the shelf in holding the casing 16 in a rigid position.

A vegetable tray 32 is receivable in the left compartment of the casing and is of sufficient length to extend throughout the 70 length of said compartment and present the lip 33 of its rim flange 34 within convenient reach to permit of the tray being easily inserted and withdrawn. The vegetable tray is preferably formed of the same type sheet 75 metal as the casing, tray and tank. Preferably, the entire device is decorated to harmonize with the finish of the refrigerator, which usually is, of course, enamel or porcelain. 80

The above-described device may be substituted for the usual pan to be found underneath the unit in refrigerators already manufactured, or may be fabricated at the time of manufacture of the refrigerator. While 85 the use of the ordinary small pan is common, however, the present invention provides not only a tray and tank for defrosting water, but also performs the additional function of 90 a hydrator or permanent place to keep vegetables and maintain them fresh and in edible condition.

Should the electricity fail or be shut off at any time, as is well known, the defrosting process starts in and, during the melting of 95 the ice from the unit, the defrosting water will be collected in the tray 21 and drained rearwardly therealong through the trough 23 to the drain pipe 24 through which it passes into the defrosting water tank 25. To remove 100 the defrosting water from the tank, it is simply necessary to place a pan or kettle under the faucet and open the faucet to allow the water to drain out of the tank.

From the above description, it is thought 105 that the construction and operation of my invention will be fully understood without further explanation.

Having thus described the invention, I 110 claim:

1. In an electric refrigerator, a casing disposed beneath the unit of the refrigerator, a vegetable tray in said casing, a defrosting water tank in said casing, there being a slot in the bottom of said casing, said tank being of less length than the casing, a drain faucet carried by said tank and registering with said slot, a tray forming a closure for the top of the casing, and a drain pipe carried by the tray projecting into said tank and anchoring the tank against displacement from the casing. 115

2. An accessory for electric refrigerators comprising a casing having longitudinal compartments therein, a defrosting water tank in one of said compartments, a vegetable tray in the other of said compartments, a defrosting water tray having a marginal U-shaped flange removably engaging the top 120 peripheral edge of the casing, the bottom 125

- wall of the tank being sloped in all directions from said flange to a diagonal line forming a trough, and a drain pipe at the low end of the trough removably received in an opening formed in said tank and anchoring said tank against dislodgment forwardly from the casing.
3. In an electric refrigerator, a casing adapted to be supported upon one of the shelves of the refrigerator below the unit of the refrigerator, downwardly projecting spaced feet on the bottom of the casing engaging portions of said shelf and preventing dislodgement of said casing, said casing being open at the front and at the top, a longitudinal partition in said casing, a defrosting water tray removably secured to the top of the casing and forming a closure for the casing, a vegetable tray in one of said compartments removable through the open front of the casing, a defrosting water tank in the other of said compartments removable through the open front of the casing, and a drain pipe carried by said defrosting water tray projecting into said tank and anchoring said tank against removal from the casing.
4. In a hydrator for electric refrigerators, a sheet metal defrosting water tray having a rim flange of substantially U-shape, the bottom of the tray sloping from the flange toward a diagonal depression which forms a trough for conducting defrosting water toward one rear corner of the tray, a drain pipe at the low point of said trough projecting below the bottom of the tray, a casing having an open top closed by said tray, a defrosting water tank in said casing having an opening receiving said drain pipe, and a vegetable tray in said casing having a rim flange disposed below said flange of the defrosting water tray adapted to be reached through the open front of the casing for withdrawing and replacing the vegetable tray.
5. A hydrator for electric refrigerators comprising a casing open at the front and at the top and provided with a longitudinal partition dividing the casing into compartments, a defrosting water tank in one of said compartments of the casing removable through the open front thereof, a vegetable tray in the other of said compartments of the casing removable through the open front thereof, a defrosting water tray forming a closure for the casing above the tank and the vegetable tray, the bottom of said defrosting water tray sloping in all directions toward a diagonal of the tray to provide a trough for conducting defrosting water rearwardly toward one corner of the tray, a drain pipe disposed at the low point of said trough and removably received in an opening formed in said tank, there being a slot in the bottom of said casing in advance of the front wall of said tank,
- and an outlet faucet housed by said casing and said defrosting water tray and registering with said slot.
- In testimony whereof I affix my signature.
